Inventor:
Harry S. Crossman
by Heard Smith & Tennant,
Atlys.

UNITED STATES PATENT OFFICE.

HARRY S. CROSSMAN, OF DORCHESTER, MASSACHUSETTS.

SHOE HEEL.

Application filed January 19, 1921. Serial No. 438,370.

To all whom it may concern:

Be it known that I, HARRY S. CROSSMAN, a citizen of the United States, and resident of Dorchester, county of Suffolk, State of Massachusetts, have invented an Improvement in Shoe Heels, of which the following description, in connection with the accompanying drawing, is a specification, like characters on the drawing representing like parts.

This invention relates to improvements in heels for shoes and the object thereof is to provide a heel having an outer shell, preferably of metal such as aluminum, or other suitable material, having a heel lift and provided with novel means for fastening the lift to the heel, and also of a construction which will enable the heel to be more easily and more firmly secured to the shoe.

I am aware that hollow metallic heels for shoes have heretofore been constructed, but various difficulties have been encountered in properly securing the lift to the heel and in so constructing the heel that it can be properly applied to the shoe. The present invention contemplates the provision of a novel form of heel in which such defects are obviated and the production of a heel which can be readily repaired or replaced by an ordinary cobbler.

A further object of the invention is to provide a heel comprising a hollow shell provided with a suitable filler or fillers, preferably of composition, so constructed that when the original lift is worn out or damaged it may be replaced by other forms of resilient or leather lifts.

A further object of the invention is to provide a heel comprising a hollow shell having a filler in the cavity thereof, provided with an anchoring plate, embedded in the upper portion of said filler, adapted to be engaged by nails or other fastenings driven through the sole of the shoe into the filler.

A further object of the invention is to provide a novel lift for shoes which may be readily replaced.

A further object of the invention is to provide a heel lift of resilient material having a surface plate firmly anchored to the body of the lift in which the periphery of

the plate terminates at a distance from the periphery of the body portion of the heel, so that the lift may be applied and fitted to different sizes of heels of other types than those having metallic shells.

Other objects and features of the invention will more fully appear from the following description and the annexed drawings and will be pointed out in the accompanying claims.

A preferred embodiment of my invention is illustrated in the accompanying drawings, in which,

Fig. 1 is a vertical sectional view of a heel and a portion of a shoe in the plane of the longitudinal axis of the shoe;

Fig. 2 is a vertical transverse sectional view of the same;

Fig. 3 is a detail vertical sectional view of the lower portion of a different heel construction, showing an improved form of lift embodying my invention applied thereto;

Fig. 4 is a detail vertical sectional view of the lower portion of a wooden heel showing a lift embodying my invention applied thereto;

Fig. 5 is a top plan view of the surface plate for a resilient heel lift embodying my invention, showing in dotted lines one of the forms of heels in which it may be embodied; and,

Fig. 6 is an edge view of said surface plate.

The present invention relates to improvements in heels for ladies' shoes, particularly of the "French" or "Louis" type, in which the surface of the upper portion of the heel is convergently curved toward the central or neck portion and from said neck portion diverges outwardly to the base of the heel. Such heels have been heretofore constructed of wood and of metallic shells, to the bottom face of which suitable lifts have been secured. Considerable difficulty has been found in the use of wooden heels for the reason that they frequently crack when being nailed to the shoe, or when the lifts are being secured to the lower faces of such heels. Where heels having metallic shells have been used difficulty has been found in properly securing the heels to the shoe and also in providing a form of lift which will not be

cut by the lower face of the metallic shell which presents a relatively narrow edge. The present invention contemplates the production of a heel in which such objections 5 will be obviated.

In the preferred embodiment of the invention illustrated herein the heel comprises a metallic shell 1 having a cavity the upper portion of which is provided with an outwardly diverging wall 2 extending upwardly from the neck portion of the heel and the lower portion of which is provided with an outwardly diverging wall 3 extending downwardly from the neck portion of the heel.

Filler members 4 and 5, preferably of a relatively light and tenacious, non-resilient, composition, are provided to fit the upper and lower portions of said cavity. Such material may be of a relatively low grade of 20 vulcanized rubber composition.

The upper filler 4 desirably is provided with a clincher plate 6 which is embedded in it a short distance below the upper surface thereof and is adapted to be engaged by the 25 ends of nails 7, or other fasteners, which are driven through the sole 8 of the shoe to secure the heel to it. The upper filler 4 also desirably is provided with an anchoring plate 9, preferably in the form of a nut, 30 adapted to receive a screw threaded end of a machine screw 10 passing upwardly through the lower filler into the upper filler. The lower filler 5 also desirably is provided with an anchoring member 11, such as a 35 washer of the type commonly used in the construction of rubber heels and the like, which forms an abutment for the head 12 of the clamping screw 10 which secures the upper and lower fillers together and serves 40 to clamp said upper and lower fillers firmly in place in the shell.

The head 12 of the clamping screw 10 desirably is provided with an axial aperture 13 having screw threaded walls adapted to 45 be engaged by a machine screw 14 for securing the lift to the heel. The clamping screw 10 may be of sufficient diameter to enable the screw threaded aperture to extend through the head into the shank of the screw. Preferably, however, the head of the screw 50 is made of sufficient length to provide a suitable seat for the screw which holds the lift upon the heel.

The anchoring member or washer 11 may 55 be constructed of any suitable size and may act as a clincher plate to engage the ends of nails driven through a leather or other usual type of lift. Preferably, however, the heel is provided with a novel form of lift which 60 may be easily attached and replaced and which will be prevented from lateral or pivotal movement when in use.

A preferred form of lift which is illustrated herein comprises a body portion 15, 65 which may be of rubber or other resilient

material, having a flat surface plate 16 secured thereto. The bottom of the heel and said plate and lift desirably are provided with interengaging means which will prevent lateral or pivotal movement of the lift 70 relatively to the heel. In the construction illustrated herein the plate 16 is provided with a flat upper surface which conforms in size to the lower face 17 of the heel. The peripheral portion of the plate is slotted and alternate portions 18, intermediate of said slits, are bent downwardly to embed within the body 15 of the lift. The plate is also provided with a relatively large central opening 19 into which the material of the body 80 15 extends. The surface plate is also provided with two or more upwardly extending prongs 20 which desirably are located in the central portion of the lift at equal distances from the center thereof and adapted to be 85 driven into the filler of the heel, or to be seated in suitable sockets in the metallic shell of the heel when the latter is constructed for such purpose. The heel lift is also provided with an anchoring or re-enforcing 90 member, preferably in the form of a washer 21, embedded in said lift at a distance below the surface plate 16. The area of said washer desirably does not exceed the area of the aperture 19. The head of the screw 95 14 seats against the washer 21 and clamps the lift firmly upon the heel. By reason of the fact that the anchoring member or washer 21 is of no greater area than the aperture 19 through the surface plate 16 of the lift, the 100 lift will not be distorted when it is clamped upon the heel, as would be the case if the area of the washer exceeded the area of the aperture in said plate, since in the latter instance the compression of the center of the 105 body portion would tend to cause the periphery to curve downwardly and separate its edges from the plate.

In the formation of the lift the surface plate is placed in the moulding and the resilient material cast upon it under pressure so that the downwardly bent portions 18 of the plate are firmly embedded in the body portion of the lift. The material of the body portion also fills the central portion 19 flush 110 with the upper surface of said plate except for a central hole through which a stud in the mould extends to support the plate 16 and which provides a hole to receive the 115 screw 14.

If desirable the mould may be used of larger size than the plate thereby providing a heel, the body portion of which is larger than the plate and which can be trimmed to enable the lift to be used on different sizes 120 of heels, such as wooden heels to which it may be secured by a screw or other suitable fastening.

A heel lift of this character is illustrated in Fig. 4 as applied to a wooden or leather 130

heel 22. In Fig. 3 the lift is illustrated as applied to a different form of heel of a well known commercial type in which the lower portion of the metallic shell 23 is provided 5 with a transverse web 24 having a threaded aperture therein to receive the screw threaded portion of a screw 25. The portion of the heel below the web 24 is provided with a filler 26 into which the prongs 20 of the surface plate are driven. Thus it will be seen 10 that the heel lift is adapted not only for use in connection with the special type of heel illustrated in Figs. 1 and 2, but also upon other types of heels.

15 It will, of course, be understood that where the lifts embodying my invention are applied to heels having metallic shells, the surface plate should be of such area as to engage, and preferably fit, the under face of 20 the heel, so that the metallic portion of the heel will rest directly upon the metallic plate and will thereby be prevented from cutting the rubber or other composition of which the resilient body of the heel is composed.

25 It will be understood that the embodiment of the invention disclosed herein is illustrative and not restrictive and that various modifications in form, construction and arrangement of parts may be made within the spirit and scope of the following claims.

Having thus described my invention, what I claim as new, and desire to secure by Letters Patent, is:

30 1. A heel for shoes comprising a hollow shell having the form of a heel, a filler within the cavity of said heel having an anchoring member embedded therein, a heel lift and means for securing the same to said anchoring member.

35 2. A heel for shoes comprising a hollow metallic shell having the form of a heel, a filler within the cavity of said heel having an anchoring member embedded therein, a heel lift, means for securing the same to said anchoring member and a clincher plate embedded in said filler adapted to bend the ends of fasteners driven through the sole of the shoe into said filler.

40 3. A heel for shoes comprising a hollow shell having the form of a heel, a composition filler therein, a clincher plate embedded in said filler adapted to be engaged by the ends of fasteners driven through the sole of the shoe into said filler.

45 4. A heel for shoes comprising a hollow shell having the form of a heel, provided with a cavity, the upper and lower portions of which have outwardly diverging walls, fillers for the upper and lower portions of said cavity, a screw having means engaging respectively the upper and lower fillers for securing them together, a heel lift and means for securing the same to one of said 50 fillers.

5. A heel for shoes comprising a hollow shell having the form of a heel, provided with a cavity, the upper and lower portions of which have outwardly diverging walls, fillers for the upper and lower portions of 70 said cavity, anchoring means embedded in said upper filler, means for securing the lower filler to said anchoring means, a heel lift and means for securing said lift to said anchoring means.

6. A heel for shoes comprising a hollow shell having the form of a heel, provided with a cavity, the upper and lower portions of which have outwardly diverging walls, composition fillers fitting the upper 80 and lower portions of said cavity, an anchoring member embedded in said upper filler, an anchoring plate embedded in said lower filler, a clamping screw connecting the anchoring members of said upper and lower fillers, a heel lift and a screw securing said lift to said clamping screw.

7. A heel for shoes comprising a hollow metallic shell having the form of a heel, provided with a cavity, the upper and lower portions of which have outwardly diverging walls, composition fillers fitting the upper and lower portions of said cavity, an anchoring member embedded in said upper filler, an anchoring plate embedded 90 in said lower filler, a clamping screw connecting the anchoring members of said upper and lower fillers, a heel lift having a surface plate engaging the under face of 95 said shell and a screw securing said lift to said clamping screw.

8. A heel for shoes comprising a hollow metallic shell having the form of a heel, provided with a cavity, the upper and lower portions of which have outwardly diverging walls, composition fillers fitting the upper and lower portions of said cavity, an anchoring member embedded in said upper filler, an anchoring plate embedded in 100 said lower filler, a clamping screw connecting the anchoring members of said upper and lower fillers, a heel lift having a surface plate engaging the under face of said shell, interengaging means upon said shell and surface plate for preventing relative lateral movement therebetween and a screw securing said lift to said clamping screw.

105 9. A lift for heels comprising a body of resilient composition having an upper surface plate provided with pointed prongs 110 projecting upwardly from its central portion, adapted to engage the heel, a central aperture to receive a fastening member and a separate anchoring member, embedded in said body at a distance below said plate 115 and in alinement with the aperture therein, also having an aperture to receive a fastening member.

120 10. A lift for heels comprising a body of resilient composition having an upper sur- 125

face plate provided with pointed prongs projecting upwardly from its central portion, adapted to engage the heel, a central aperture to receive a fastening member and a separate anchoring member embedded in said body at a distance below said plate having an area not to exceed the area of

the aperture in said plate and provided with an aperture to receive a fastening member.

In testimony whereof, I have signed my name to this specification.

HARRY S. CROSSMAN.
